José Brito, Havana, Cuba

Application July 29, 1954, Serial No. 31,646

Claims priority, application Cuba January 29, 1954

Term of patent 14 years

(Cl. D4—5)

Fig. 1

To all whom it may concern:

Be it known that I, José Brito, a citizen of the Republic of Cuba, residing at Havana, Cuba, have invented a new, original, and ornamental Design for a Disposable Paper Toilet Seat Cover, of which the following is a specification, reference being had to the accompanying drawing, forming a part hereof.

I claim:

The ornamental design for a disposable paper toilet seat cover, as shown.
